(57) **CLAIM**

The ornamental design for a display panel with animated graphical user interface for gate boarding information, as shown and described.

DESCRIPTION

The file of this patent contains at least one drawing/photograph executed in color. Copies of this patent with colored drawing(s)/photograph(s) will be provided by the Office upon request and payment of the necessary fee.

FIG. 1 is a front view of a first image in a sequence of images of a display panel with animated graphical user interface for gate boarding information in a first embodiment of the new design;

FIG. 2 is a front view of a second image thereof;

FIG. 3 is a front view of a third image thereof;

FIG. 4 is a front view of a first image in a sequence of images of a display panel with animated graphical user interface for gate boarding information in a second embodiment of the new design;

FIG. 5 is a front view of a second image thereof; and,

FIG. 6 is a front view of a third image thereof.

The outermost broken line showing of a display screen and the other broken line showing of elements of the graphical user interface illustrate portions of the article and do not form part of the claimed design.

The appearance of the animated graphical user interface transitions sequentially between the images shown in FIGS. 1-3 and FIGS. 4-6. The process or period in which one image transitions to another forms no part of the claimed design.
